UNITED STATES PATENT OFFICE

154,010

DESIGN FOR A SLIP OR SIMILAR ARTICLE

Seamon Wolf, New York, N. Y.

Application November 26, 1947, Serial No. 142,809

Term of patent 3½ years

(CL. D3—26)

To all whom it may concern:

Be it known that I, Seamon Wolf, a citizen of the United States of America, residing in New York city, county of New York, and State of New York, have invented a new, original, and ornamental Design for a Slip or Similar Article, of which the following is a specification, reference being had to the accompanying drawing, forming part thereof, wherein:

I claim:

The ornamental design for a slip or similar article, substantially as shown.

SEMON WOLF.
